R. ROSNER

BY-PASS VALVE FOR GAS WASHING APPARATUS

Filed Oct. 29, 1926

UNITED STATES PATENT OFFICE.

RUDOLPH ROSNER, OF CHICAGO, ILLINOIS.

BY-PASS VALVE FOR GAS-WASHING APPARATUS.

Application filed October 29, 1926. Serial No. 145,004.

This invention relates to a by-pass valve for gas washing apparatus, and has for one of its objects to provide a simple and compact valve especially adapted for use with 5 gas washing apparatus.

It is a further object of this invention to provide a light non-breakable valve for use with laboratory gas washing bottles, and further to provide clamping means for securely connecting the valve and gas washing 10 bottle.

Other and further important objects of this invention will be apparent from the disclosures in the specification and the accompanying 15 drawings.

This invention (in a preferred form) is illustrated in the drawings and hereinafter more fully described.

On the drawings:

20 Figure 1 is an elevational view of a device embodying the principles of my invention illustrated as attached to a gas washing bottle, with parts in section.

Figure 2 is a top plan view of the same.

25 Figure 3 is a sectional view taken on line III—III of Figure 1.

Figure 4 is an enlarged sectional view taken substantially on line IV—IV of Figure 2, with parts removed.

30 Figure 5 is a sectional view similar to Figure 4 showing the valve in a different position.

Figure 6 is a sectional view taken on line VI—VI of Figure 4.

35 Figure 7 is a sectional view taken on line VII—VII of Figure 6.

As shown on the drawings:

In Figure 1 there is shown a by-pass valve, indicated as a whole by the numeral 40 1, operatively secured to a gas washing bottle 2. Said gas washing bottle 2 is here illustrated as a standard flat bottom glass flask partially filled with a washing or absorbing fluid 3, through which the gas is 45 adapted to be passed. It will be understood that in place of the gas washing bottle 2 any other type of washing apparatus may be substituted, the present embodiment being merely for the purpose of illustrating my invention.

50 Said valve 1 comprises a globular body portion 4 having a flared lower extension 5 provided with downwardly extending spaced annular flanges 6 and 7. Said spaced flanges 55 6 and 7 provide a recess 8 for receiving a suitable gasket 9 sealing the joint between the

valve 1 and the bottle 2, said bottle 2 being provided with a flanged neck 10 against the upper surface of which the gasket 9 is adapted to press. The inner flange 7 is preferably 60 of such diameter as to extend within the neck of the flask or bottle 2 to increase the stability of the joint. The valve body portion 4 is further provided with an upwardly projecting lug or abutment 11 having a conical 65 end 12, for a purpose that will later appear. Said valve 1 is preferably formed of some light metal such as aluminum.

For the purpose of securing the valve 1 to the gas washing bottle 2 there is provided a clamp 13. Said clamp 13 comprises a clamping portion 14 formed of U-shaped members 15 and 16 adapted to encircle the neck of the flask 2 and an end piece 17 adapted to be secured to the ends of said U-shaped 75 member 16 by means of bolts 18. Said U-shaped member 16 is further provided with lugs 18a having threaded vertical apertures 19. Said apertures 19 are adapted to receive a pair of vertical tie bolts 20 carrying a 80 cross bar 21. Said cross bar 21 is adapted to straddle the upwardly projecting lug 11 of the valve 1 and to bear against the conical point 12 when the tie bolts 20 are screwed into clamping position. Said tie bolts 20 are 85 provided with slotted heads 22 to receive a screw driver for tightening or unloosening the clamp.

The by-pass valve 1 is provided with aligned horizontal nipples 23 and 24 formed 90 integral with said body portion 4 and centrally passaged to provide inlet and outlet passages 25 and 26, respectively. Said nipples 23 and 24 are provided with tapered ends 27 and 28 for connection with suitable 95 conduits 29 and 30. The valve body portion 4 is further provided with a central passage 31 extending downwardly through an integral sleeve 32. Said sleeve 32 is adapted to receive the upper end of a tube 100 33, the lower end of said tube 33 extending below the surface of the fluid 3 in the gas washing bottle 2. An offset vertical passage 34 extends parallel to the central passage 31 and communicates with the outlet passage 105 26, a continuous passage thus being afforded for the escape of the washed gases from the bottle 2. A plug cock 35 extends through said body portion 4 at right angles to the axes of the inlet and outlet passages 25 and 110 26, respectively. Said plug cock 35 is formed with a spherical enlarged head 36

adapted to be rotatably seated in a recess 37 formed in said body portion 4. The front end of said plug cock 35 is provided with a threaded stem 38 for receiving a threaded sleeve 39, said sleeve 39 being adapted to be received in a recess 40 in said body portion 4 for the purpose of holding the plug cock 35 in position. The extended end of the stem 38 is provided with a handle 41 for manipulating the plug cock. Said plug cock 35 is provided with a bore 42 extending completely therethrough, and a second bore 43 at right angles thereto extending through one face only of said plug cock 35. Said bores 42 and 43 are thus arranged in the form of a T, as is common in three-way cocks. The barrel of said plug cock 35 is further provided with a recess 44 in its face opposite the bore 43. As shown in Figure 4 20 said recess 44 is adapted to register with the outlet passage 26 and the offset passage 34 when the plug cock is in one position. In that position the bore 43 registers with the inlet passage 25 and forms with the bore 42 25 a continuous passage into the tube 33. In this position, therefore, gas entering the inlet passage 25 will flow down through the tube 33 into the fluid 3 in the gas washing bottle 2. The washed gas will, of course, 30 bubble up to the surface of the fluid 3 and escape through the neck of the bottle into the offset passage 34, which, as has been explained, is in unrestricted communication with the outlet passage 26.

35 In the second position of the plug cock 35, as shown in Figure 5, the bore 42 forms a continuous communication with the inlet and outlet passages 25 and 26, respectively, and the bore 43 is in inoperative position. 40 Accordingly the gas entering the inlet passage 25 is by-passed over the tube 33. It will be noted that the offset passage 34 is partially open when the plug cock is in this position, but this would have no effect as 45 far as the by-passing of the gas is concerned, since the gas washing bottle 2, being already filled above the fluid 3 with gas or air, there is little or no tendency of the gas to pass downwardly through the passage 34.

50 In order to limit the movement of the plug cock 35 there is provided a pin 45 extending inwardly from the inner face of the spherical head 36 and adapted to move in a groove 46 formed in the valve body portion 55 4. Said groove 46 is so positioned and of such length as to limit the movement of the pin 45 to an arc of 90°. The pin 45 therefore limits the rotation of the plug cock 35 in one extreme position to the position 60 shown in Figure 4, and in the other extreme position to that shown in Figure 5. A marker 47 on the periphery of the handle 41 indicates at what position the plug cock may be.

65 It is thus apparent that I have provided a

simple and compact by-pass valve that is peculiarly adapted for use with gas washing apparatus. A valve such as described is much more satisfactory than the usual type of three-way cock and is more serviceable than glass plug cocks such as are ordinarily used in laboratory work.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. A by-pass valve for gas washing apparatus, comprising a body portion adapted to be mounted on a receptacle containing a washing fluid, said body portion having aligned horizontal inlet and outlet passages, a central downwardly extending passage and an offset passage parallel to said central passage and in open communication with said outlet passage, a tube secured in said central passage and adapted to extend below the surface of the fluid in said receptacle, and a plug-cock for said body portion having 3-way bores therein, said bores in one position of said plug-cock being adapted to establish communication between said inlet and outlet passages to by-pass the gas around the receptacle and in another position to establish communication between said inlet passage and said central passage whereby the gas is caused to pass through said tube into the fluid in the receptacle, the undissolved gases escaping through said offset passage into said outlet passage.

2. In combination, a by-pass valve having a lower flanged portion adapted to be mounted upon a container in the washing apparatus and an upper projecting lug, a clamp adapted to be secured to the container, a cross bar adapted to contact said lug, and tightening means joining said cross bar and clamp to clampingly secure said valve to said container.

3. In combination, a by-pass valve adapted to be mounted on the top of a neck portion of a container, and a tube connected to said valve and extending downwardly through said neck portion and into a liquid in the container, said valve including an inlet adapted to be connected to said tube to deliver gas into said container, and an outlet connected to the interior of the said neck portion of said container for discharging the gas from the container after it has passed through said liquid.

4. In combination, a by-pass valve adapted to be mounted on the top of a neck portion of a container, a tube connected to said valve and extending downwardly through said neck portion and into a liquid in the container, said valve including an inlet adapted to be con-

nected to said tube to deliver gas into said container, and an outlet connected to the interior of the said neck portion of said container for discharging the gas from the container after it has passed through said liquid, said valve having a body including a flange cooperable with the flange on the upper end of the neck portion of the container, and means for clamping said flanges together 5 comprising a pair of cooperable clamp members disposed about said flanges and detachably anchored to each other.

5. In combination, a by-pass valve adapted to be mounted on the top of a neck portion of a container, and a tube connected to said valve and extending downwardly

through said neck portion and into a liquid in said container, the valve including an inlet adapted to be connected to said tube to deliver gas into said container, and an outlet 20 connected to the interior of the said neck portion of said container for discharging the gas from the container after it has passed through said liquid, said valve including a three-way rotatable cock, said valve having 25 a passageway communicating with one of the openings in the cock, telescoped by the end of said tube.

In testimony whereof I have hereunto subscribed my name.

RUDOLPH ROSNER.
